PATTERN SELECTION CABINET

Harold E. Nock, Newburyport, Mass., assignor to
 Towle Manufacturing Company, Newburyport,
 Mass., a corporation of Massachusetts

Application October 14, 1932, Serial No. 637,751

1 Claim. (Cl. 312—107)

This invention relates to a pattern selection cabinet more particularly for the display of the newer silverware patterns which a store may not desire to stock until their popularity is determined. 5 Accordingly a cabinet is provided in the form of a chest of drawers, in which each drawer except the upper one may have therein a representative selection of pieces of a new pattern, but the upper drawer may contain a lesser number of pieces 10 of each of the several new patterns contained in the other drawers. By reason of a glass cover on the cabinet the pieces of the several patterns contained in the top drawer are continually on display. Again the upper drawer may be filled 15 with pieces of a single new pattern for display purposes and the lower drawers used to show a customer other patterns if not attracted by the one on display.

Because stores do not ordinarily purchase even 20 samples of all new silverware patterns, but limit themselves to a selected number varying with different stores, the cabinet is sectional in its construction. Thus, with the upper or display section, a store may have one, two, or more lower 25 sections as the needs of its business require. The size of the cabinet is such that it may conveniently rest on a table or on the counter thus placing the upper or window section at a convenient height for the customer's inspection of the silverware there- 30 in displayed.

These features of the invention will be best understood and appreciated from the following description of the preferred embodiment thereof shown in the accompanying drawing, in which:

35 Figure 1 is a perspective view of a sectional pattern selection cabinet constructed in accordance with the invention;

Fig. 2 is a perspective view of one of the cabinet 40 drawer receiving sections;

Fig. 3 is a sectional view through one of the drawer receiving sections; and

Fig. 4 is a perspective inverted view of the transparent cover member for the cabinet.

The improved pattern selection cabinet is made 45 up of a plurality of rectangular sections 10 having a bottom 11, side walls 12 and a rear wall 14 the top edges of which are plane and flush with each other, see Fig. 2. Their bottoms also are flush as shown. Several such sections are shown 50 as stacked together in Fig. 1 to form a sectional cabinet which may be composed of any desired number of sections. A suitable base 15 is provided for supporting the sections and a top or cover 16, in the form of a frame 17 about a pane of glass 55 18, is adapted to rest on the top section and pro-

vide a display window. The front end of each section 10 being open, adapts them to receive drawers 20 within which selections of different patterns of silverware may be suitably arranged for display beneath the glass 18 which is co-extensive with the drawer opening (compare Figs. 2 and 4). For this purpose each drawer is fitted with the usual covered supports for knives, forks, spoons and the like comprising silver flatware.

The several sections 10 which have no inherent 10 means for preserving vertical alignment may be secured together in stacked relation by any suitable means which will secure and hold them together as a rigid unit, as shown in Fig. 1. The means preferably utilized for this purpose comprises a pair of angle clips 24 secured at each side of the bottom of each section and similarly secured to the cover frame 17. It will be understood that the base 15 is so constructed that no securing 15 clips are necessary on the bottom section of the cabinet. The clips are formed to provide depending perforated portions 25 that overlap the sides of the adjacent lower section and screws extending through these perforations and into such sections, secure the sections together as a unit. The secured leg of each clip 24 is set flush in the bottom 11 of each section and in the frame 17 of the cover, see Figs. 3 and 4, to create tight joints between the flush tops and bottoms of the sections and permit use of the interchangeable 20 drawers 20 while insuring their easy "running". Any desired number of drawers may be used between the cover and base.

In modern merchandising the more expensive 25 and finer grades of silverware may not be kept in stock for sale, samples being maintained for display and selling purposes, the customer ordering 30 from the samples. The convenient and attractive displaying of such merchandise as silverware is an important factor and the improved 35 display cabinet is particularly adapted to this purpose. Each drawer may contain a single pattern of the silverware and each drawer may be labeled with the pattern name plate 26, as shown 40 in Fig. 1. The newest pattern may be located in the top drawer, to be continually on display, but any one of the other drawers may instantly be substituted therefor in order to place the pattern therein on display. As illustrated in Fig. 1 45 the top drawer contains a few pieces each, of several patterns, larger selections of which may be found in the several underlying and labeled 50 drawers.

The nature and scope of the invention having 55 been indicated, and its preferred embodiment

having been specifically described, what is claimed as new, is:—

5 A pattern selection cabinet composed of a stack of open front sections each consisting of a floor, two side walls and a rear wall, the top edges of said three walls being all in one plane and the bottom of the section being wholly in a single parallel plane, whereby said sections are devoid of interfitting construction and in any 10 order in which they may be piled the upper section will present a plane top face, a drawer fitting into each section the front of each drawer closing the open front of its section and the floor of

the section above forming a cover for each drawer except for the drawer in the top section, a transparent cover for said top drawer consisting of a glass adapted to display the contents of the drawer and a frame holding said glass laid upon the edges of the top section, and means for holding said sections and top frame from relative movement when stacked, said sections all being of the same size whereby the top drawer may be replaced by any other drawer and vary the pattern displayed beneath the transparent cover. 10
